Primary Examiner — Cynthia Ramirez*(74) Attorney, Agent, or Firm* — Sheridan Ross P.C.(57) **CLAIM**

The ornamental design for a lift level, as shown and described.

DESCRIPTION

FIG. 1 is a perspective view of a lift level according to an embodiment of the claimed design;

FIG. 2 is a front elevation view of the lift level of FIG. 1; FIG. 3 is a rear elevation view of the lift level of FIG. 1; FIG. 4 is a right elevation view of the lift level of FIG. 1; FIG. 5 is a left elevation view of the lift level of FIG. 1; FIG. 6 is a top plan view of the lift level of FIG. 1; and, FIG. 7 is a bottom plan view of the lift level of FIG. 1. For accuracy with the elected embodiment, the special broken line description immediately before the claim has been deleted from the specification.
